UNITED STATES PATENT OFFICE.

WILLIAM J. SIMMONS, OF ATLANTA, GEORGIA, ASSIGNOR TO KNIGHTS OF THE KU KLUX KLAN, OF ATLANTA, GEORGIA, A CORPORATION OF GEORGIA.

DESIGN FOR A BADGE.

Application filed May 25, 1925. Serial No. 13,563. Term of patent 14 years.

To all whom it may concern:

Be it known that I, WILLIAM J. SIMMONS, a citizen of the United States of America, residing at Atlanta, in the county of Fulton and State of Georgia, have invented a new, original, and ornamental Design for a Badge, of which the following is a specification, reference being had to the accompanying drawing, forming a part hereof.

In the drawing:

Fig. 2 is an edge view of the same.

I claim:

The ornamental design for a badge, as shown.

WILLIAM J. SIMMONS.
